(57) **CLAIM**

We claim the ornamental design for a wristband health tracker, as shown and described.

DESCRIPTION

All of the material from the U.S. Design patent application Ser. No. 29/468,517 which is essential to the claimed design is included herein. Any material in this application which is not present herein forms no part of the claimed design.

FIG. 1 is an isometric view of a wristband health tracker looking at the top, front, and right sides.

FIG. 2 is a further isometric view of the wristband health tracker looking at the top, back, and right sides.

FIG. 3 is a further isometric view of the wristband health tracker looking at the bottom, back, and left sides.

FIG. 4 is a further isometric view of the wristband health tracker looking at the bottom, front, and left sides.

FIG. 5 is a right side view of the wristband health tracker.

FIG. 6 is a left side view of the wristband health tracker.

FIG. 7 is a top view of the wristband health tracker.

FIG. 8 is a bottom view of the wristband health tracker.

FIG. 9 is a front view of the wristband health tracker.

FIG. 10 is a back view of the wristband health tracker; and, FIG. 11 is an isometric view of the wristband health tracker looking at the top, front, and right sides.

The “fitbit” logo and the markings “L/G” are shown in dashed lines in these views and do not form part of the claimed design.

The broken line showing of structural features is included for the purpose of illustrating non-claimed subject matter and forms no part of the claimed design.
